UNITED STATES PATENT OFFICE

FREDERICH W. WOOD, OF KANSAS CITY, MISSOURI, ASSIGNOR TO BERRY-WOOD PIANO
PLAYER CO., OF KANSAS CITY, MISSOURI.

NOTE-SHEET-GUIDE MECHANISM.

No. 901,930.

Specification of Letters Patent.

Patented Oct. 20, 1908.

Application filed May 28, 1907. Serial No. 376,152.

To all whom it may concern:

Be it known that I, FREDERICH W. Wood, a citizen of the United States, residing at Kansas City, in the county of Jackson and 5 State of Missouri, have invented certain new and useful Improvement in Note-Sheet-Guide Mechanism, of which the following is a specification.

This invention relates to musical instrument players and more especially to automatic note-sheet guide mechanism for such 10 players, of that class whereby the lateral creepage of the note sheet results in its restoration to normal position before any of 15 its perforations can be moved entirely out of alinement with their respective tracker bar passages, the object of the present invention being to produce a guide mechanism which shall respond to an almost imperceptible lateral creepage of the note-sheet and 20 instantly effect the restoration of the note sheet to its true path and thus insure a full and proper registration of each note sheet 25 perforation with its respective tracker bar passage.

With this general object in view the invention consists in certain novel and peculiar features of construction and organization as hereinafter described and claimed; and in 30 order that it may be fully understood reference is to be had to the accompanying drawings in which—

Figure 1, is a top plan view, partly broken away, of a note-sheet guide mechanism embodying my invention. Fig. 2, is a vertical transverse section of the same with a part broken away to expose other features of construction more clearly. Fig. 3, is a fragmentary view to show more clearly the means 35 for adjusting a part hereinafter described. Figs. 4 and 5 are plan views of a part of the valve casings. Figs. 6 and 7 are vertical sections of the casings shown respectively at Figs. 4 and 5.

In the said drawings, 1 indicates end frames connected at their upper and lower front corners by tie rods 2 and 3 respectively and at their rear sides by a tie rod 4, which rod 4 may be a roller if desired, the 45 parts named constituting a framework.

A rock frame mounted at its front end on rod 3 as a pivot, comprises a pair of arms 5 connected by a cross bar 6 and said rock

frame is held yieldingly elevated by a spring 7 of the type shown or of any other suitable 55 or preferred type, for the purpose of holding a roller 8, in such position as to coöperate with a driven roller hereinafter described, in feeding the note sheet, also hereinafter referred to. 60

9 indicates a short shaft journaled in one end of frame 1 and provided at its inner end with a crank or pin 10 and at its outer end with a thumb piece 11, the latter being to enable the person in control to operate 65 and quickly turn said shaft and through the instrumentality of said crank either force the rock frame downward or permit spring 7 to raise it.

12 indicates the note sheet of the endless 70 or any preferred type extending upward from a casing, not shown, at the front side of rod or roller 4 and at the rear side of a roll 13 journaled in the upper rear corners 75 of the framework. From roll 13 the note sheet extends downwardly and forwardly around the flanged roll 14 also journaled in the framework. From roll 14 the note sheet extends rearwardly and around the rear side of a roll 15 journaled in the framework, and 80 from said roll around the front side of a suitably driven roller 16, and from the latter down and around the rear side of roller 8 hereinbefore referred to and hence down into the casing. Between rolls 14 and 15, 85 the note sheet engages the tracker bar 17 provided with the customary tracker bar passages 18 and depending tubes 19 for connection with the air-exhausting mechanism, 90 not shown.

At one end the tracker bar is provided in its front edge with a notch 20 and extending across said notch in parallel relation and longitudinally of the tracker bar is a guide pin 21 and a headed screw 22, said screw 95 being reduced to provide the non-threaded portion 23, journaled in the tracker bar and the shoulder 24 to prevent the screw from moving longitudinally when turned.

25 is a block fitting in notch 20 and mounted slidingly on pin 21 and having a threaded relation with screw 22 so that when the latter is turned said block may be moved toward the headed end of the screw. Said block 25 is provided with a pair of passages 26 and 27 one in front of the other and so dis-

posed that one side of each is in line with the center of the other as shown clearly in Figs. 1 and 3, it being noticed by reference to the last-named figure that by this arrangement it is possible for the note sheet to completely cover passage 26 and at the same time partially cover passage 27, it being further noted that these passages are of oblong rectangular form but are disposed at right angles to the passages 18 in order to have the required cubical air-capacity and yet require a lateral creepage almost imperceptible, of the note sheet for partly uncovering the covered passage 26 or completely covering the partially covered passage 27.

28 and 29 indicate tubes secured at their upper end to block 25 and communicating with passages 26 and 27, respectively, and 30 is a retractile coil spring secured at one end to said block and at the other to the tracker bar in any suitable manner for the purpose of adjusting the block inwardly of the tracker bar when the screw 22 is turned to permit such movement.

31 indicates a rod disposed rearward of and preferably out of contact with the note sheet above rod or roller 4 and 32 indicates a pair of guide rods supporting rod 31 and extending slidingly through guide brackets 33 secured to the framework, the front ends of said rods 32 being attached by eye-bolts 34 or otherwise to the movable sides of a pair of pneumatics 35 and 36, secured to the framework at its front side and opposite ends in any suitable manner, springs 37 secured to the pneumatics and engaging rock frame bar 6 tending to hold the pneumatics normally expanded as shown in Fig. 2. The pneumatics 35 and 36 are equipped with tubes 38, connected by flexible tubes, not shown with tubes 39 and 40 of valve casings 41 and 42 respectively. Each casing is provided with a chamber 43 connected to its respective tube, with an exhaust chamber 44 connected through tubes 45 with air exhausting apparatus, not shown, and with chambers 46, the chamber 46 of the casing 41 having a tube 47 connected by a flexible tube not shown, with tube 28 communicating with passage 26 of slide block 25. Chamber 46 of casing 42 likewise has a tube 48 connected by a flexible tube, not shown, with tube 29 communicating with passage 27 of said block and said chambers 46 are connected with their respective exhaust chambers 44 by vent holes 49.

The partitions of the casings separating chambers 43 and 44 are provided with openings 50 and the partitions between chambers 44 and 46 of the casing have openings covered by flexible diaphragms 51, and secured to said diaphragms are valve stems 52 extending up through openings 50, openings 53 in the tops of the casings, and through guide bars 54 and 55 of said casings respectively.

56 is a valve mounted on the valve stem 52 of casing 41 in chamber 43 and normally covering the contiguous opening 50. 57 is a similar valve mounted on stem 52 of casing 42 in chamber 44 and normally covering opening 50 of such casing, the valve-stem of the last-named casing being also provided with a valve 58 adapted at times to cover and close opening 53 of such casing but normally leaving such opening uncovered.

From the above it will be seen that normally air is free to enter both pneumatics through the openings 53 of the respective valve casings and coöperate with the springs 37 in holding the pneumatics expanded and the rod 31 behind and out of contact with the note sheet, the latter being adapted when the rock frame is operated to cause roller 8 to press the note sheet against the driven roller 16, to impart movement to said sheet downward between the driven roller 16 and roller 8. Should the note sheet swerve laterally so as to uncover passage 26, air would enter chamber 46 of casing 41 and press the diaphragm upwardly and raise valve 56 until the same uncovers opening 50 and closes opening 53, the result being the suction in chamber 44 would, through the connecting tubes described effect the collapse of pneumatic 35 and thus pull the end of rod 31 connected to said pneumatic forward until it exerted pressure against the corresponding side of the note sheet and caused the same to swerve in the opposite direction and re-cover said passage 26, the re-covering of the passage resulting in the return of the diaphragm and valve of the connected casing to their original positions and the re-expansion of the connected pneumatic.

Should the note sheet swerve and completely cover passage 27, it would cut off the passage of air to chamber 46 of casing 42, which action would be instantly followed by the downward movement of diaphragm 51 and the valve stem with its valve 57 and valve 58; the movement of the former opening communication between the exhaust chambers 43 and 44 and cutting off communication between chamber 43 and the atmosphere by the simultaneous downward movement of valve 58. As a result the suctional action from chamber 44 would effect the collapse of the pneumatic 36 and through the connections described cause the corresponding end of rod 31 to move forward and engage the note sheet and thereby cause the latter to resume its original position and thus readmit air to passage 57, it being understood that the uncovering of said passage 27 results in the return of the diaphragm and valves of the connected casings to their original positions and the re-expansion of the connected pneumatic.

I am aware of the patent on automatic

note sheet guide mechanism #755950 is issued March 29, 1904, James D. Smith inventor, which shows one of the rollers over which the note sheet runs, capable of being tilted upward at one end or the other to cause the note sheet to move or creep laterally toward the lower end of said roll and I also have a pending application for patent on tracker-bars for piano players filed Dec. 14, 1906, Ser. No. 347,899 in which is embodied an adjustable block provided with a pair of openings, one of which is adapted to be normally exposed by the note sheet. This invention differs from the patent referred to in that it is provided with a rod to be thrown at one end or the other into engagement with the note sheet and over which the note sheet travels only when so thrown, and this bar is not a permanent guide for the note sheet like said roller. My co-pending application referred to is directed chiefly to the adjustable block provided with a pair of openings to which construction no special claims are directed in this application other than to a block provided with a pair of passages disposed in a line substantially at right angles to the line in which the tracker bar passages are arranged.

From the above description it will be apparent that I have produced a note-sheet guide mechanism for musical instrument players possessing the features of advantage enumerated as desirable and I wish it to be understood that I do not desire to be restricted to the exact details of construction shown and described as obvious modifications will suggest themselves to one skilled in the art.

Having thus described the invention what I claim as new and desire to secure by Letters Patent is:—

1. In a mechanism of the character described, the combination of a series of guide rolls, and a tracker bar arranged parallel with said rolls and provided with a longitudinal series of air passages, of a perforated note sheet running over said rolls and tracker bar, a rod contiguous to the note sheet and disposed substantially parallel with said rolls and tracker bar and means for causing said rod to assume a position at an angle to its normal position and apply pressure at one end on the note sheet at one side of the longitudinal center of the same, to cause said note sheet to creep or swerve laterally toward the opposite end of said rod.

2. In a mechanism of the character described, the combination of a series of guide rolls, and a tracker bar arranged parallel with said rolls and provided with a longitudinal series of air passages, of a perforated note sheet running over said rolls and tracker bar, a rod contiguous to the note

sheet and disposed substantially parallel with said rolls and tracker bar, a pair of pneumatics linked to the opposite ends of said rod, and means whereby the lateral swerving of the note sheet toward one side shall result in the operation of the pneumatic at such side and cause the same to move the corresponding end of said rod into frictional engagement with the note sheet at the corresponding side of its longitudinal center and compel said sheet to swerve in the opposite direction.

3. In a mechanism of the character described, the combination of a series of guide rolls, and a tracker bar arranged parallel with the rolls and provided with a longitudinal series of air passages, of a block arranged at one end of the series of tracker bar passages, and provided with a pair of air passages arranged at right angles to the series of tracker bar passages, each of said block passages having one side substantially in line with the center of the other, and a perforated note sheet running over said rolls in a direction parallel to that of the passages of the block and engaging the tracker bar and blocks and normally uncovering one of the passages of the latter and partially covering the other passage of the same.

4. In a mechanism of the character described, the combination of a series of guide rolls and a tracker bar arranged parallel with the rolls and provided with a longitudinal series of air passages, of a block arranged at one end of the series of tracker bar passages, and provided with a pair of air passages arranged at right angles to the series of tracker bar passages, each of said block passages having one side substantially in line with the center of the other, a perforated note sheet running over said rolls in a direction parallel to that of the pair of passages of the block and engaging the tracker bar and blocks and normally covering one of the passages of the latter and partially covering the other passage of the same, and means for swerving the note sheet toward the passage of the block described as normally partially uncovered should the note sheet swerve in the opposite direction and uncover the companion passage of said block.

5. In a mechanism of the character described, the combination of a series of guide rolls and a tracker bar arranged parallel with the rolls and provided with a longitudinal series of air passages, of a block arranged at one end of the series of tracker bar passages, and provided with a pair of air passages arranged at right angles to the series of tracker bar passages, each of said block passages having one side substantially in line with the center of the other, a perforated note sheet running over said rolls in

a direction parallel to that of the passages of the block and engaging the tracker bar and blocks and normally covering one of the passages of the latter and partially covering the other passage of the same, and means to swerve the note sheet in the proper direction to partially uncover the passage described as partially uncovered normally,

should the note sheet swerve and cover said passage.

In testimony whereof I affix my signature, in the presence of two witnesses.

FREDERICH W. WOOD.
